[57] **CLAIM**

The ornamental design for an automotive truck service module, substantially as shown and described.

DESCRIPTION

FIG. 1 is a front perspective view of the automotive truck service module showing our new design;

FIG. 2 is a plan view of the undersurface thereof;

FIG. 3 is a front elevation view thereof;

FIG. 4 is an elevation view of the right side thereof; and

FIG. 5 is an elevation view of the left side thereof.

The top of the service module is substantially unornamented and follows the contour of the top edges shown in FIGS. 3, 4 and 5.
